UNITED STATES PATENT OFFICE

ANDREW J. KREIN, OF BALTIMORE, MARYLAND, ASSIGNOR TO THE FAULTLESS MANUFACTURING COMPANY, OF BALTIMORE, MARYLAND, A CORPORATION OF MARYLAND

UNION UNDERGARMENT

Application filed December 9, 1929. Serial No. 412,585.

The present invention relates broadly to garments and more specially to an undergarment commonly known as a union suit.

The present improvement relates to the construction of a union suit undergarment whereby the garment, when in normal use on the wearer, comprises a form-fitting garment, and at other times is a loose fitting garment.

10 The improved construction has to do more specially with the back of the garment and particularly with a part of the back herein called a "posterior apron" member formed integral with the back. This apron member is attached permanently and securely to one side back seam which normally tends to hang substantially vertical on the wearer, and the fastening button for the posterior apron is mounted upon the opposite side 15 back seam of the garment, which forms a secure anchorage for the button so it is not liable to tear out in use and at the same time places stresses on the garment, through the reinforcement of the garment due to the 20 seam, whereby these forces are distributed in the garment in such manner as to cause the garment to be form conforming. The top edge of the posterior apron comprises an elastic portion to which the cloth forming the apron part is attached by means of 25 gathers so that when the top edge of the apron is buttoned over the anchoring button the elastic portion pulls inwardly on both of the said side seams, thereby taking 30 up any looseness in the garment and making the same substantially conform to the wearer, consequently forming a very comfortable garment. The elastic portion, when buttoned in place, permits a yielding to the 35 back of the garment during bending of the wearer and again contributes to the comfort of the garment. When the edge of the posterior apron is removed from the button the stress due to the elastic member is released 40 and the garment tends to hang loosely from the shoulders of the wearer. The back of the garment beneath the apron comprises an arched edge to the garment which is finished in the usual way with these edges being attached to the side seams of the garment. 45

The edge adjacent the open side of the apron extends downwardly and is attached to the side seam adjacent the leg of the garment so that when the posterior apron is unloosened from the button a substantially free opening is provided and the garment tends to hang vertically from the wearer, providing suitable looseness in the garment to permit the same to be moved around the body as may be desired. The preferred type of 55 elastic material for the upper edge of the posterior apron is that disclosed in the Harsh Reissue Patent No. 16,641. It is to be understood, however, that any other suitable elastic material may be satisfactory for 60 this purpose and that while the Harsh type of construction is preferred, the invention is in no way limited to the character of the 65 elastic used.

Other and further objects of the present 70 invention will in part be obvious and will in part be pointed out hereinafter by means of the accompanying drawings which illustrate a preferred form of the invention. It is to be understood, however, that the disclosure 75 herewith is for the purpose of illustration of the invention and is not to be considered in the limiting sense.

Fig. 1 is a back view of the garment with the posterior apron unbuttoned from the 80 anchoring button.

Fig. 2 is a back view of the garment with the posterior apron buttoned in place and illustrating the form conforming feature of the invention.

Fig. 3 illustrates the posterior apron 85 loosened and pulled aside to illustrate the arched construction to the lower part of the upper back portion of the garment.

Fig. 4 illustrates the setting of the anchor- 90 ing button over the side seam.

Referring now more especially to the drawings, the garment comprises an upper back portion 1 sewed to side portions 2 and 4 by means of side seams 5 and 6. The lower part of the upper portion 1 is cut away to form an arched shaped finished edge 7 which terminates in an elongated reinforcing edge part 8. The posterior apron 9 is sewed into the side seam 6 at one edge and 95 100

at the other edge is unattached for its major length being attached to the side seam 5 at the point 10, which leaves a triangular shaped freely movable piece of material comprising the posterior apron 9.

The upper edge of the posterior apron 9 comprises an anchoring piece 11 sewed into the side seam 6 and to which is attached a belt member 14 of elastic material, preferably the material disclosed in the Harsh Reissue Patent No. 16,641; it being understood, however, that any type of elastic webbing or other satisfactory elastic material may be used for the belt member 14. The 15 posterior apron 9 is provided with a mid seam 12 and is gathered at its upper edge where it is attached to the belt 14 in such manner as to permit the belt to expand freely without restriction due to the cloth of the 20 posterior apron. An anchoring button 15 is sewed upon and through the side seam 5, and the end reenforcement 16 of the belt member 14 is provided with a buttonhole 17 adapted to cooperate with this anchoring 25 button 15.

The garment is provided with the usual neck opening 18 and arm openings 19 and 20. The front of the garment is provided with the usual full length opening closed by 30 buttons 21.

The garment when in normal use on the wearer with the belt 14 buttoned over the anchoring button 15 conforms to the body of the wearer in that the elastic belt 14 pulls 35 inwardly on the side seams 5 and 6, thereby distributing the pulling stresses throughout the sides of the garment and taking up slack material around the waist of the wearer, at the same time allowing elasticity in case the 40 wearer bends or moves the body in such manner as to place stresses on the elastic belt 14. The arched opening 7 is located sufficiently beneath the upper edge of the belt 14 so that a complete covering is provided 45 for the wearer when the posterior apron is buttoned in place and at the same time the anchoring edge or reenforcing edge 8 of the upper portion 1 of the garment forms a substantial overlap along the side 50 of the opening for the posterior opening and thoroughly protects the body of the wearer. When the posterior apron is released by removing the buttonhole 17 from the anchoring button 15, the garment tends 55 to resume straight lines with substantial fullness so that the garment is easily moved around the body of the wearer.

Having described my invention, I claim:

1. An undergarment of the union suit 60 type comprising side members and a back portion, substantially longitudinally extending seams joining said side members to said back portion, said back portion comprising an upper part terminating at the lower 65 end in an arched edge extending between

said side seams, a posterior apron attached throughout its length to one side seam and unattached at the top and the other edge, the arched portion of the back extending below the said unattached portion of the apron, 70 anchoring means carried by one of the side seams adapted to secure said apron in place to cover said arched edge, and an elastic belt member comprising the upper edge of said apron and with the cloth of said apron being gathered where it is attached to said belt member whereby the elastic belt pulls said side seams inward at the back to cause the garment to be body conforming adjacent the waist thereof when said apron is 80 closed.

2. A union suit undergarment having side members and a back, said side members being joined to said back by longitudinally extending side seams, said back comprising an upper portion and a lower portion overlapping said upper portion, an elastic belt having one end permanently anchored to one of said seams and with the other end free, said belt comprising the upper edge of said lower portion, anchoring means on the free end of said belt, and securing means mounted on the side seam adjacent the free end of said belt whereby said belt may be anchored to said securing means to retain said lower portion in position to close the back of said garment to cause said garment to be body conforming adjacent the waist thereof. 90

3. A union suit undergarment comprising a back, side seams extending the full length of said garment, said back comprising an upper portion extending between said side seams and a lower portion including the back portion of the legs of said garment with the lower portion having an upper free edge and one side edge free to form a posterior apron, an elastic belt comprising the top edge of said posterior apron and with the material gathered adjacent said belt to permit said belt to be stretched, one end of said belt being anchored to one of said side seams, and means to anchor the free end of said belt to the other side seam, whereby the elastic pull of said belt is delivered to the side seams of said garment during the normal wear of said garment whereby said garment is body conforming adjacent the waist thereof. 100

4. A union suit undergarment comprising a back and a front, side seams extending the full length of said garment, said back having an upper portion extending between said side seams and a lower portion including the back portion of the legs of the garment, said lower portion having an upper edge and a portion of one side edge free to provide a triangular flap on the upper part of said lower portion, said upper portion of the back having an elongated reenforcing edge part extending down one side seam be- 110 120 125 130

neath the free side edge of the flap when
the flap is closed; an elastic belt comprising
the top edge of said flap and with the ma-
terial gathered adjacent said belt to permit
said belt to be stretched, one end of said
belt being secured to one of said side seams;
and means carried by the other side seam
to anchor the free end of said belt, whereby
the elastic pull of said belt is delivered to
the side seams of said garment during the
normal wear of the garment so that the
garment is body conforming adjacent the
waist.
